UNITED STATES PATENT OFFICE.

WILLIAM HANDLER, OF NEWARK, NEW JERSEY.

HANDLE.

1,272,948.

Specification of Letters Patent. Patented July 16, 1918.

Application filed February 28, 1917. Serial No. 151,410.

To all whom it may concern:

Be it known that I, WILLIAM HANDLER, a citizen of the United States, and a resident of Newark, in the county of Essex and State 5 of New Jersey, have invented certain new and useful Improvements in Handles, of which the following is a description.

My invention relates to handles, and more particularly to a reinforced handle for suit 10 cases, bags, satchels and the like. One of the objects of my invention is to provide an improved handle of this character which will be of great strength and durability and which is of simple construction and capable 15 of being economically manufactured.

Another object of my invention is to provide a handle wherein all relative movement of the component parts thereof will be prevented and which will retain its shape when 20 subjected to heavy loads.

Still further objects of my invention are to provide an improved construction wherein practically none of the strains on the handle is imposed directly on the outer coverings 25 of the handle, and wherein the outer surface of the handle is free from rough seams or protuberances, whereby the wear on the handle is reduced to a minimum and the same will be easy and comfortable to the 30 hand.

Other objects and features of my invention will be hereinafter more specifically described and claimed.

In order that my invention may be more 35 clearly understood, attention is directed to the drawing forming part of this specification, which illustrates a preferred embodiment of my invention, and in which:

Figure 1 is a perspective view of the 40 handle;

Fig. 2 is a longitudinal sectional view thereof, partly in elevation, taken on line 2-2 of Fig. 3; and

Fig. 3 is a transverse sectional view taken 45 on line 3-3 of Fig. 2.

Referring to the drawing, reference character A represents the filler member or wickle of the handle which is preferably composed of a central part 1 consisting of a 50 piece of rope or similar material and which is preferably strengthened, enlarged and shaped to conveniently conform to the hand between its end portions as by means of a triangular piece of paper 2 or other suitable 55 flexible material wound thereon. The paper

2 is so wound on the member 1 that the wickle will be thickest in the middle, as clearly shown in Figs. 2 and 3. The wickle or filler member A is suitably secured to the central portion of a flat fairly heavy piece 60 3 of leather or like material, as by means of a suitable adhesive, the leather piece 3 preferably being coextensive with the filler member or wickle A. In order to render the handle strong and durable, a preferably flat 65 reinforcing member 4, preferably formed of steel, hard fiber or other suitable stiff material, is disposed between the filler member or wickle A and the leather piece 3, and is preferably co-extensive with members A 70 and 3. To maintain the reinforcing member 4 in proper position relative to the other parts of the handle, the same is preferably permanently and rigidly secured to the lower side of the wickle A, preferably by 75 the last few windings of the piece of paper 2, as shown in Figs. 2 and 3. A covering strip 7 of suitably finished flexible material, preferably leather, is fitted closely about the wickle A and securely fastened, preferably 80 by sewing, to the bottom leather piece 3. The side portions 8 of the covering strip 7 beyond where the latter is sewed to the leather piece 3 are turned upwardly and 85 backwardly into close engagement with the main portion thereof between where it is sewed to the piece 3. Bag supporting rings 5 are placed on the end portions of the composite member formed of the wickle A, leather piece 3, reinforcing strip 4, and covering strip 7, and said end portions are then 90 bent downwardly and backwardly against the under side of the main portion of the leather strip 3 to form the end loops 6 of the handle. These bent end portions are 95 securely fastened to the under side of the leather strip 3 as by tacking or pasting the same thereto. It will be apparent that portions 7' of the covering strip 7 will overlie and form a covering for the inner sides of 100 the loops 6. A filler 9, preferably of leather, is firmly secured to the under side of the leather piece 3 preferably by being sewed to the latter between the ends of the composite member made up of members A, 3, 4 and 7, 105 as shown in Fig. 2. The side portions of the leather piece 3 and the leather filler 9 are bent and worked upwardly about the sides of the filler or wickle A and the covering 7 thereof, until they lie closely in engagement 110

with the same and with each other. The exterior portions of the bent up-side portions of the filler 9, leather piece 3 and covering strip 7 are then shaved and finished off fairly evenly in any suitable manner, as shown in Fig. 3. The members 3, 7 and 9 are preferably suitably held together in the positions into which they are worked and bent, as by means of a suitable adhesive. The handle is now bent and worked substantially to the shape which it is desired the same shall have when completed. After the handle has been worked to this shape, a covering 10, preferably of leather and having the desired exterior finish, is applied to the bottom and sides of the handle, and the edge portions of covering 10 are turned over the edges of the filler 9 and leather piece 3 and forced down tightly between the portions of the covering piece 7 which cover the sides of the wickle A and the upwardly extending portions 8 of the covering piece 7, in which position they are securely held as by means of a suitable adhesive. The covering pieces 7 and 10 of the handle B, which is now in the form shown in Fig. 1, are finished smoothly in order that there will be no protuberances or other roughness which might callous the hand. The handle is now complete and ready to be applied to the bag, suit case or the like for which it is adapted.

It will be obvious that with a handle constructed as above described, practically all strains imposed thereon will be taken up by the reinforcing member or strip 4 and that this reinforcing member will prevent the handle from being twisted or otherwise misshapen by heavy loads or strains imposed thereon. Moreover, all the parts of the handle are securely fastened together in such a manner as to prevent any relative movement thereof even after the same has been used for a long time.

While I have shown and described the preferred embodiment of my invention, it is to be understood that various changes and modifications may be made therein without any departure from the spirit of the invention and the scope of the appended claims.

Having now described my invention, what I claim and desire to protect by Letters Patent is as follows:—

1. A handle comprising a filler member or wickle, a bottom member, and a reinforcing member of stiff material disposed between said bottom member and a portion of said filler member, all of said members being substantially co-extensive and secured together, the end portions of said members being bent into loops for the reception of rings or the like adapted to be applied to a bag, substantially as described.

2. A handle comprising a filler member or wickle, a bottom member, and a reinforcing member of stiff material disposed between

said bottom member and a portion of said filler member, all of said members being substantially co-extensive and secured together, the end portions of said members being bent downwardly and backwardly underneath the main portions thereof into loops for the reception of rings or the like adapted to be applied to a bag, substantially as described.

3. A handle comprising a filler member or wickle, a bottom member, and a metallic reinforcing member disposed between said bottom member and a portion only of said filler member, all of said members being substantially co-extensive and secured together, the end portions of said members being bent into loops for the reception of rings or the like adapted to be applied to a bag, substantially as described.

4. A handle comprising a filler member or wickle, a bottom member, a reinforcing member of stiff material disposed between said bottom member and a portion of said filler member, all of said members being substantially co-extensive and secured together, the end portions of said members being bent into loops for the reception of rings or the like adapted to be applied to a bag, and a filler disposed between the ends of said members, substantially as described.

5. A handle comprising a filler member or wickle, a bottom member, a reinforcing member of stiff material disposed between said bottom member and a portion of said filler member, all of said members being substantially co-extensive and secured together, the end portions of said members being bent downwardly and backwardly underneath the main portions thereof into loops for the reception of rings or the like adapted to be applied to a bag, and a filler disposed underneath and secured to said members between the ends thereof, substantially as described.

6. A handle comprising a filler member or wickle, a bottom member, and a reinforcing member of stiff material disposed between said bottom member and a portion of said filler member, all of said members being substantially co-extensive and secured together, the end portions of said members being bent into loops for the reception of rings or the like adapted to be applied to a bag, said filler member or wickle comprising stiffening means between the bent end portions thereof, substantially as described.

7. A handle comprising a filler member or wickle, a bottom member, and a reinforcing member of stiff material disposed between said bottom member and a portion of said filler member, all of said members being substantially co-extensive and secured together, the end portions of said members being bent into loops for the reception of rings or the like adapted to be applied to a bag, said filler member being stiffened, enlarged

and shaped to conform to the grip of the hand between the bent end portions thereof, substantially as described.

8. A handle comprising a filler member or wickle, a bottom member, a reinforcing member of stiff material disposed between said bottom member and a portion of said filler member, all of said members being substantially co-extensive and secured together, 10 the end portions of said members being bent into loops for the reception of rings or the like adapted to be applied to a bag, a filler disposed between the ends of said members, and a substantially smooth covering for all 15 said members and said filler, substantially as described.

9. A handle comprising a filler member or wickle consisting of a flexible member and stiffening means comprising a sheet of flexible material wound thereon, a flexible bottom member, and a reinforcing member secured to said wickle or filler member between a portion of the latter and said bottom member by one or more of the windings of 25 said sheet of flexible material, substantially as described.

10. A handle comprising a filler member or wickle, a bottom member, a reinforcing member disposed between a portion of said filler member and said bottom member, a covering fitting closely over said filler member and secured to said bottom member, said covering having its side portions turned upwardly and back onto the main portion 35 thereof, all said members and covering being substantially co-extensive and having their end portions bent downwardly and backwardly underneath the main portions thereof into loops for the reception of bag supporting rings, the side portions of said bottom member being turned upwardly and over the upwardly turned side portions of said covering, a filler disposed underneath and secured to said bottom member between 40 the bent end portions of said filler, bottom and reinforcing members, the side portions of said filler extending upwardly into close engagement with the outer surfaces of the upwardly extending side portions of said 45 bottom member, and a coating of flexible material covering the bottom and sides of the handle and having its side portions turned downwardly over the edges of said bottom member and covering and fitting 50 closely between the turned up side portions of the covering of said wickle or filler member and the portions of the latter covering the sides of the wickle, substantially as described.

- 60 11. A handle for bags, suit-cases, and the like, comprising a wickle, and a reinforcing element, said reinforcing element having portions thereof contacting with outer surface-portions of the wickle and being 65 also partially embedded in said wickle, said

wickle and reinforcing element having their end portions bent to provide receiving loops, and an outer covering for said wickle and reinforcing element.

12. A handle for bags, suit-cases, and the like, comprising a wickle, and a reinforcing element, said reinforcing element having portions thereof contacting with outer surface-portions of said wickle, said wickle and reinforcing element having their end portions bent to provide receiving loops, and an outer covering for said wickle and reinforcing element, combined with a central piece arranged between the ends of the said loop-shaped end portions, and an additional 75 covering mounted upon said central piece and the said loop-shaped end portions, said second-mentioned covering being connected at its longitudinal marginal edges with the longitudinal marginal edges of said first- 80 mentioned covering.

13. A handle, comprising a wickle, a reinforcing member extending longitudinally of said wickle and having flat end portions, a layer of flexible material also extending 90 longitudinally of said wickle, and shaped to the same, said layer and reinforcing member having their end portions bent into loops for the reception of rings or the like adapted to be applied to a bag, and an outer covering for said parts having inwardly turned edge portions for securing the covering in position, said reinforcing member being of stiffer material than said wickle and layer. 95

14. A handle, comprising a wickle or filler member, a reinforcing member extending longitudinally of the same and having flat end portions, a layer of flexible material also extending longitudinally of said filler member, and shaped to the same, said layer 100 and reinforcing member having their end portions bent to provide loops, an outer covering extending over said filler member, a central filler piece arranged between the ends of said loop-shaped end portions, and an additional covering upon said central filler piece and layer, said first named covering being connected at its longitudinal marginal edge portions with the longitudinal marginal edge portions of said second 110 mentioned covering, said marginal edge portions being directed inwardly of the handle, and said reinforcing member being of stiffer material than said layer and filler piece. 115

15. A handle, comprising a wickle, a bottom member, a flat reinforcing member extending longitudinally of said wickle and bottom member, said members having their end portions bent to provide loops, an outer covering extending over said wickle, a central filler piece arranged between the ends of said loop-shaped end portions, and an additional covering mounted upon said filler piece and the bottom member, said first-mentioned covering being connected at its 120 125 130

longitudinally marginal edges with the longitudinal marginal edges of said second-mentioned covering and said reinforcing member being of stiffer material than said wickle, bottom member, center piece and coverings.

16. A handle, comprising a filler member, a bottom member, a reinforcing member extending longitudinally of said filler member and bottom member and having flat end portions, said bottom member and reinforcing member having their end portions bent into loops for the reception of rings or the like adapted to be applied to a bag, and
- 15 means covering said members, said means having inwardly turned longitudinal edge portions, and said reinforcing member being of stiffer material than said other members and said covering means.
- 20 17. A handle, comprising a filler member or wickle, a bottom member, and a reinforcing member of stiff material disposed between said bottom member and a portion of

said filler member and having flat end portions, all of said members being approximately coextensive and secured together, the end portions of said members being bent into loops for the reception of rings or the like adapted to be applied to a bag.

18. A handle, comprising a filler member or wickle consisting of a flexible member and stiffening means comprising a sheet of flexible material wound on said flexible member, a flexible bottom member, and a reinforcing member secured to said wickle or 35 filler member between a portion of the latter and said bottom member by one or more of the windings of said sheet of flexible material, a portion at least of said reinforcing member being flat.

This specification signed and witnessed this 23rd day of February, 1917.

WM. HANDLER.
